CLAIM

The ornamental design for a puzzle table as shown and described.

DESCRIPTION

FIG. 1 is a front, right and top perspective view of a puzzle table, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 1; and,

FIG. 12 is an enlarged view of detail 12 in FIG. 2.

The dashed broken lines depict portions of the puzzle table that form no part of the claimed design. The dot-dash broken lines surrounding details shown in FIGS. 1-2 and 9-12 are for purposes of annotating the enlarged views only and form no part of the claimed design.
